UNITED STATES PATENT OFFICE.

EDWARD T. HAILS, OF MONTGOMERY, ALABAMA.

METHOD FOR CLEANING PHONOGRAPH-RECORDS.

1,378,344.

Specification of Letters Patent. Patented May 17, 1921.

No Drawing.

Application filed February 4, 1920. Serial No. 356,319.

To all whom it may concern:

Be it known that I, EDWARD T. HAILS, a citizen of the United States, and a resident of the city and county of Montgomery, 5 State of Alabama, have invented certain new and useful Improvements in Methods for Cleaning Phonograph-Records, of which this is a specification.

The invention relates to the cleaning or 10 surface renovation of soft records such as are used nowadays in the dictating phonographs in commercial use. The object of the invention is to provide a simple, inexpensive, efficient and readily employed 15 method and means essential thereto, for rapidly renewing the surface of a used record so that the dictation thereon—or the record trace thereof—may be quickly removed and the record suitably smoothed or 20 re-surfaced so that another trace may be impressed upon it.

The usual method and means employed 25 for this purpose—the shaving machine, effects a very satisfactory re-surfacing, but the object of this invention is to eliminate 30 the necessity for such a machine and permit the operator to immediately wipe off the previous record and prepare the record for further use without employing any machinery whatever.

I have found that by wiping a record 35 with a rag moistened with a hydrocarbon solvent such as gasoline, kerosene oil, or benzine, as examples, the original trace can be obliterated so that the record will not now “talk”; but this treatment, alone, leaves the surface so rough that a very disagreeable sound is produced from the inequalities of surface—so much so that it is 40 unpleasant for the ear to listen to a trace taken from a record cleaned in this way and then traced anew. If, however, after the record has been first cleaned with the hydrocarbon solvent, say wiped with a cloth or rag wet 45 with kerosene, it is then further treated by being wiped with a smooth rag moistened with the mixture which is the means contemplated in this invention, the record surface is at once made so smooth and free 50 from rough spots that it is quite as satisfactory as the best shaved record or as an unused record, fresh from the factory. I find that the mixture which must be used on the record, first roughly treated with hydrocar-

bon solvent such as kerosene oil, and which I have very successfully employed in practice, is one of alcohol, ether, and vinegar, the proportions being variable, though a mixture of substantially equal parts of the three answers very well indeed. The alcohol may be methylated spirits and preferably should be so, as economy is an object and the wood alcohol answers perfectly. This mixture, wiped on the roughly smoothed record, as would be expected, almost immediately evaporates and leaves the record surface practically free from odor, and with a pleasant surface. No particular care is necessary in employing my method; the used record is wiped with a soft rag wet 70 with kerosene; the mechanical friction and the kerosene breaking down the ridges and furrows into which the tracing point has cut the surface; then, or within a few seconds—or minutes—the mixture mentioned is 75 applied with another rag or cloth or with the fingers. This leaves the record surface very smooth and quite ready for a new trace to be inscribed. I do not pretend, of course, that this method produces a perfectly cylindrical new surface, but this is not necessary, as it is enough that the new surface is so smooth that when used again nothing will affect the reproducing stylus except the dictation trace and that external vibrations 80 due to roughness of the record surface are suitably eliminated. The method does this much very satisfactorily indeed: It produces a new surface which can be dictated against with the certainty that in listening 85 to the trace external noises will be quite as slight as if the record had been carefully shaved on the usual screw-fed shaving machine—equivalent, as is well known, to a screw cutting lathe. The use of my method, 90 however, not only dispenses with the need of such a machine but the whole process of the two steps or stages—the rough cleaning by wiping with a kerosene-wet rag, and the final wiping with my mixture—can be done 95 100 in a minute at most.

I know, of course, that attempts have been made to remove trace and smooth a record by wiping with a solvent such as kerosene and that this is not new. My method, however, as pointed out, involves an essential step carried much further. It includes the subsequent application of the particular

mixture described which results in a surface which cannot even be approximated by the use of a solvent alone.

Having described my invention what I claim is:—

1. The method of resurfacing phonograph cylinders set forth consisting in first obliterating the record trace by wiping the record with a solvent such as kerosene and then 10 wiping the record with a mixture of alcohol, ether and vinegar.
2. The method described, consisting in smoothing records roughly surfaced by previous wiping with a solvent of the record 15 material by wiping such records with a mix-

ture of an acid, ether, and alcohol, substantially as set forth.

3. The method set forth, consisting in wiping a used phonograph record with a hydrocarbon solvent such as kerosene, until the record trace is substantially obliterated; and then wiping the record so treated with a mixture of wood alcohol, ether and vinegar.

Witness my hand this Feb. 2, 1920.

EDWARD T. HAILS.
